UNITED STATES PATENT OFFICE

FRANZ LAWACZECK, OF MUNICH, GERMANY, ASSIGNOR TO WORTHINGTON PUMP AND MACHINERY CORPORATION, OF NEW YORK, N. Y., A CORPORATION OF VIRGINIA

HYDRAULIC MACHINE

Application filed May 19, 1926, Serial No. 110,266, and in Germany January 19, 1926.

My invention relates to hydraulic machines and more especially to turbines, rotary pumps and the like. It is an object of my invention to provide means for creating in a machine of this type improved conditions of flow.

It is an established fact that a definite peripheral velocity must be imparted to the whirling body of liquid in the machine and to the rotor in order to obtain an efficient exchange of energy, but the problem of axial velocity has not yet been fully investigated, the only rule laid down so far being that the axial velocity must be constant throughout the area of the suction pipe.

The body of liquid on the opposite side of the rotor from the suction pipe, that is, the body in front of the rotor in turbines, and at the rear of the rotor in pumps, constitutes a whirling flow which carries a definite amount of kinetic and potential energy for a given machine and a given power input or output at the rotor. As a rule only the potential energy is utilized and it is therefore desirable to change the kinetic energy of this whirling flow into potential energy. Obviously this change should be brought about under conditions of maximum efficiency, that is, substantially without loss. However, the change can only be effected under conditions of maximum efficiency if the flow of the body of liquid is not disturbed in any way but the energy-carrying components of the whirl are carried in a regular manner.

This condition is fulfilled according to this invention by so designing the casing of the machine that the clearance, that is, the radial distance between the water-contacting surfaces of its walls which control the flow of liquid on the opposite side of the rotor from the suction pipe, is reduced with increasing radial distance of such walls from the axis of the rotor. The radial distances of the water-contacting surfaces of the walls increase with increase of their distance from the suction pipe.

It is thus possible to keep the axial velocity constant, not only in the suction pipe, but throughout the body of the water, and this

is the condition for the regular continuation of its flow.

The most favorable control of the flow in the body of liquid beyond the rotor is obtained by shaping the water-contacting surfaces of the inner and outer walls of the casing between which the liquid is flowing so that they coincide with the surfaces of coaxial paraboloids which are preferably congruent for each wall and are displaced axially. In this embodiment of the invention the cross-sectional area of the liquid-passage between the inner and outer water-contacting surfaces of the walls in any plane normal to the axis is the same as the cross-sectional area in any other plane normal to the axis, or, in other words, the cross-sectional areas in radial planes have a constant value.

Preferably the clearance between the walls of the casing, measured radially, is inversely proportional to their radius, that is, their radial distance from the axis of the rotor.

In the drawings affixed to this specification and forming part thereof machines embodying my invention are illustrated diagrammatically by way of example.

In the drawings

Fig. 1 is an axial section of a rotary pump,

Fig. 2 is an elevation of this pump, partly in section on the line 2—2 in Fig. 1,

Fig. 3 is an axial section of a hydraulic turbine.

Figs. 4, 5 and 6 are axial sections illustrating modifications. These three figures will be described with reference to a turbine, but it will be understood that they may be applied to pumps or other rotary machines without departing from the spirit of my invention.

Referring to Figs. 1 and 2, *b* is the rotor of the pump to the shaft *c* of which rotation is imparted by any suitable means, such as for instance an electric motor *M*. Water is supplied to the rotor *b* through a suction pipe *a* and a cylindrical extension *a'* of a spiral casing *s* from which it is discharged through a delivery pipe *s'*, this spiral casing having a spiral liquid passage increasing in radial cross-sectional area in the direction of flow.

Referring to Fig. 3, *B* is the boss of the rotor, *C* is its shaft, *S* is the preferably spiral

water conduit, S' is the casing of the turbine, A' is a cylindrical extension of the casing, and A is the suction pipe connected to this extension.

5 The parts described with regard to the pump and the turbine are well known in the art and may be designed as desired without departing from the spirit of my invention.

In both cases, that is in the case of the 10 pump, where the rotor b imparts motion to the water, as well as in the case of the turbine, in which motion is imparted to the rotor B by the water, the passage e (or E) in the casing which is connected with the suction 15 pipe a (or A) is constituted by walls d' and d'' (or D' and D'') which are arranged at an angle to the axis f (or F) of the machine and are preferably so curved that the boss b' (or B') of the rotor which is the continuation 20 of the inner wall, is convex.

The most favorable condition for the flow 25 in the passage e (or E) after leaving the rotor of the pump, or before flowing through the rotor of the turbine, is that the clearance of the passage e (or E) should be regularly decreased as the radial distance of both its walls d' , d'' (or D' , D'') from the axis f (or F) is increased. Preferably the radial clearance $r-o$ (or $R-o$) is inversely proportional to the corresponding radius r (or R) at that point, and the walls are formed on congruent paraboloids, the vertices v' and v'' (or V' and V'') of which are displaced axially.

30 In the simplest case as illustrated in Figs. 1 to 3, the vertex v'' (or V'') of the inner paraboloid is substantially in the radial plane in which the outer paraboloid intersects the cylindrical extension a' (or A') of the suction pipe. This plane contains the line g (or G). This position of the inner paraboloid with regard to the line g (or G) is in accordance with the condition of constant axial velocity, for at this point the cylindrical 35 suction duct a' or (A') becomes extended into the outer paraboloid wall d' (or D') of the casing so that the area of the duct is gradually increased and this increase is made up for by a corresponding reduction 40 which is effected at this point by the insertion of the inner paraboloid.

A passage e (or E) formed by two coaxial paraboloid walls is equally suitable for pumps and for turbines. In either case the 45 suction from or the delivery to the suction pipe is constant as the axial velocity in the body of liquid is also constant. In machines of the usual type the axial velocity varies quite irregularly within the machine and 50 there is no fixed ratio of the suction pipe velocity and the axial velocity in the other parts of the machine.

In the case of a turbine it is well known that the operation of the suction pipe is very delicate and that it is most important to ob-

tain a regular flow in the body of water beyond the rotor. In a turbine which is designed as described and illustrated in Fig. 3, where the whirling body of the water is conducted to the suction pipe A , A' at constant 70 axial velocity by the walls of the passage E , the only function of the rotor is to intercept the whirling body and to exhaust its energy without in any way interfering with the constancy of the axial velocity.

The boss b (or B) constitutes a spreader which maintains the axial velocity of the water exactly constant beyond the suction pipe.

Fig. 3 illustrates by way of example the 80 combination of a passage E as described with a water supply passage h in which guide vanes h' are arranged so that the water is conducted to the casing S' radially, as usual in turbines. These radial guide vanes may 85 be arranged at any suitable distance from the rotor B .

Similarly in a pump a diverging passage e' of any desired length may be inserted between the passage e and the spiral casing.

It may be desirable to increase the diameter of the boss B of the rotor for mechanical or hydraulic considerations. In this case, as shown in Fig. 4, the area of the suction pipe A is restricted by the extended boss B' of the rotor. In order to obtain constant axial velocity in this machine, the vertex V'' of the inner paraboloid is displaced further into the suction pipe A beyond the line G and preferably so far that the inner paraboloid intersects the radial plane through the junction of the outer paraboloid with the inner wall of the suction pipe, the position of this plane being indicated by the line G .

If, as shown in Fig. 5, one or more guide vanes h are provided in the passage E with the object of changing velocity into pressure or vice versa, the reduction of the area by these vanes should be considered in adapting the walls D' and D'' to the condition of axial velocity throughout. Therefore the walls D' and D'' are not shaped at these points as exactly congruent paraboloids but, as indicated in dotted lines at h' , the clearance between them is increased in proportion to the 115 restriction of the area.

It may be necessary or desirable to consider other factors when determining the configuration of the walls, for instance when the walls are rough. Whatever may be the configuration of the walls, it should comply with the fundamental condition that the clearance between the walls must be reduced with their increasing radial distance from the rotor axis.

In the examples shown and described the boss of the rotor has been shown as being convex toward the suction pipe. The degree of convexity is determined, as is also the configuration of the passage e (or E), by the 130

condition that the axial velocity should be constant. Variations in the paraboloid shape of the walls of said passage which are imposed by any factors, such as for instance, the vanes h in Fig. 5, and variations due to additional displacement of the vertices of the two paraboloids which may become desirable in order to consider any such factors, will never exert an influence on the configuration 10 of the passage by which this condition of convexity is reversed. However it may be desirable to arrange the vertex of the inner paraboloid not in the line g (or G) but beyond it, so that the boss projects a certain 15 distance into the suction pipe as shown in Fig. 6.

I wish it to be understood that I do not desire to be limited to the exact details of construction shown and described, for obvious 20 modifications will occur to a person skilled in the art.

I claim:

1. A hydraulic machine comprising a rotor, a casing, and a suction pipe, said casing 25 having on that side of the rotor opposite the suction pipe an annular liquid passage, the water-contacting surfaces of the walls of said liquid passage being formed to coincide with surfaces of paraboloids.

2. A hydraulic machine comprising a rotor, a casing, and a suction pipe, said casing having on that side of the rotor opposite the suction pipe an annular liquid passage, the water-contacting surfaces of each of the walls 35 of said passage being formed to coincide respectively with the surfaces of two paraboloids co-axial with the axis of said rotor and displaced axially with regard to each other.

3. A hydraulic machine comprising a rotor, 40 a casing, and a suction pipe, said casing having on that side of the rotor opposite the suction pipe an annular liquid passage, the water-contacting surfaces of each of the walls of said passage being formed to coincide respectively with the surfaces of two paraboloids, the suction pipe joining the outer wall in a plane transverse to the axis of the rotor, which plane is intersected by the paraboloid 45 surface of the inner wall.

4. A hydraulic machine comprising a rotor, a casing, and a suction pipe, said casing having on that side of the rotor opposite the suction pipe an annular liquid passage, the water-contacting surfaces of each of the walls 55 of said passage being formed to coincide respectively with the surfaces of two paraboloids, the suction pipe joining the outer wall in a plane transverse to the axis of the rotor, which plane contains the vertex of the paraboloid surface of the inner wall of said liquid passage.

5. In a hydraulic machine comprising a rotor, a casing, and a suction pipe, said casing having on that side of the rotor opposite the 60 suction pipe an annular liquid passage, the

water-contacting surfaces of each of the walls of said passage being formed to coincide with the surfaces of two paraboloids which are co-axial with the axis of said rotor and displaced axially with regard to each other, said suction pipe being joined to the outer wall in a plane 70 transverse to the axis of the rotor, said plane containing the vertex of the inner paraboloid which coincides with the surface of the inner wall of said liquid passage.

6. A hydraulic machine comprising a suction pipe, a casing having an inner cylindrical wall portion joining said suction pipe, a rotor having vanes whose outer ends lie on the surface of an imaginary cylinder, said ends rotating in close proximity to the said inner cylindrical wall portion of the casing, said casing having on that side of the rotor opposite the suction pipe an annular liquid 80 passage whose mean radius increases with increase of its distance from a plane through the rotor, the clearance between the walls of said annular liquid passage decreasing with said increase of radius, said annular liquid passage being arranged to conduct liquid 85 as a liquid annular body free to rotate about one axis of the annular body while permitting the liquid to travel bodily in the general direction of said axis of rotation.

In testimony whereof I affix my signature. 95
